UNITED STATES PATENT OFFICE.

WALTER M. A. GALE, OF TORONTO, ONTARIO, CANADA, ASSIGNOR OF ONE-HALF TO
ARTHUR LAWRENCE CARROLL, OF TORONTO, ONTARIO, CANADA.

BINDER.

1,412,857.

Specification of Letters Patent. Patented Apr. 18, 1922.

Application filed February 12, 1921. Serial No. 444,468.

To all whom it may concern:

Be it known that I, WALTER M. A. GALE, a resident of the city of Toronto, in the county of York, Province of Ontario, 5 Canada, a subject of the King of Great Britain, have invented certain new and useful Improvements in Binders, of which the following is a specification.

This invention relates to improvements in 10 binders used in filing loose leaf forms, and my object is to devise a binder which will be very simple and cheap to manufacture and which will be very efficient in operation.

15 The invention is illustrated in the accompanying drawings in which—

Fig. 1 is a longitudinal view of part of a binder, the upper clamping member being shown in section;

20 Fig. 2 a detail showing a slight modification of the device;

Fig. 3 a plan view of one of the locking members; and

25 Fig. 4 a view similar to Fig. 1 showing a modification of the lock releasing means.

Fig. 5 is a detail top plan view showing the arrangement of the slides and their operating means as shown in Fig. 4.

In the drawings like numerals of reference indicate corresponding parts in the different figures.

30 1 is the bottom clamping member, which in practice will be bound as an integral part of the base or back of the binder. To this member 1 are secured the binding posts 2 in any suitable manner. 3 is the upper clamping member having the usual holes therethrough to enable it to slide on the posts 2. This upper member 3 will, as 35 usual, preferably be bound with and form an integral part of the cover of the binder.

40 This upper member will be formed as a flat hollow tube. Within each end of the upper member 3 is a locking lever 4 having a hole 5 therein towards one end adapted for the passage of the posts 2, the hole 5, however, being of very slightly greater diameter than the posts 2 and lying in alignment with the holes in the members 3. The

45 50 edges of the hole 5, however, will preferably be rounded off. The sides 6 of the other end of each lever 4 are bent downwardly to form supports on which the levers are adapted to rock. The center 7 of the end 55 is left extending substantially in the plane

of the lever and normally extends into opening 8 in the upper surface of the upper member 3.

To retain the locking levers within the upper clamping member, I form slots 9 between the holes 5 and the ends of the levers, and through these slots are passed pins 10 permanently secured inside the member 3.

The ends of the locking levers will normally tend to drop towards the bottom of 65 the member 3 at an angle to the latter, but the engagement of the sides of the post in the holes 5 will be such that the ends of the levers will not be allowed to quite touch the bottom of the member 3 so that the 70 levers will exercise a cramping action against the sides of the posts to prevent the raising of the member 3 on the posts 2. Pressure on the ends 7 through the 75 openings 8 will raise the levers to a position parallel with the top of the member 3, when the member 3 may be easily lifted on the posts 2.

If desired, the ends 7 of the locking levers may be bent down slightly as shown in 80 Fig. 2, and headed pins 11 extending through the upper side of the member 3 secured thereto.

In Fig. 4 I show a modification of the means for releasing the locking levers 4. 85 A sliding plate 12 is arranged at each side of a stem 13 extending up through the upper surface of the member 3 and provided with a suitable head by which it may be rotated. This stem has a cam-shaped end 90 having its greatest width normally lying transversely of the member 3. When the stem 13 is rotated a quarter circle, the plates 12 are pushed forward to raise the lowered ends of the levers 4, the plates 12 being 95 provided with tapered ends to assist their entry beneath the ends of the levers. Pins 15 are secured to the upper surface of the sliding plates to keep the plates in their proper position. A bent spring 16 passes 100 around the pins 15 nearest the stem 13, which tends to return the plates to their normal position.

With reference to my preferred construction as shown in Figs. 1, 2 and 3, it will be 105 noted that the same parts may be used for posts any distance apart and that the locking levers may be inserted in the member 3 with their parts 6 on which they rock located between the two posts 2 instead of 110

between the ends of the member 3 and the posts.

It will also be seen that with my preferred construction shown in Fig. 1 that 5 only the posts 2 project above the upper surface of the member 3. This is of great importance when the binder is being bound with canvas or leather as is usually done, as any projections interfere with the covering of the parts, and it is not even necessary to cut away the canvas or leather over the openings 8, as there is enough give in this material to allow of the release of the locking levers.

15 It will also be found that the locking levers will grip equally as well if the edges of the holes 5 are rounded off instead of being left sharp.

From the above description it will be 20 seen that I have devised a construction which will satisfactorily attain the objects of my invention as set out in the preamble of this specification.

What I claim as my invention is:—

25 1. In a binder, the combination of a base; posts secured to the base; a tubular clamping member having holes therein for the passage of said posts; pins in said clamping member locking levers within said member each lever having an opening therethrough through which one of said pins loosely passes and an opening in alinement with the holes in the clamping member, the last mentioned opening being of slightly 35 greater diameter than the posts, a downward extension at one end of each of said levers on which the levers may rock to engage the sides of the posts with a cramping action; and means for rocking said levers to dis- 40 engage them from the posts.

2. In a binder, the combination of a base; posts secured to the base; a tubular clamping member having holes therein for the passage of said posts; locking levers within said members having openings therethrough 45 in alinement with the holes in the clamping member, said openings being of slightly greater diameter than the posts; a downward extension at one end of each of said levers on which the levers may rock to engage 50 the sides of the posts with a cramping action; an actuating extension on each of said levers beyond the downward extension in substantially the same plane as the surface of the lever, said clamping member 55 having openings in its upper surface through which the actuating extensions may be engaged and depressed to release the levers from their engagement with the posts.

3. In a binder, the combination of a base; 60 posts secured to the base; a tubular clamping member having holes therein for the passage of said posts; locking levers within said members having openings therethrough 65 in alinement with the holes in the clamping member, said openings being of slightly greater diameter than the posts; a downward extension at one end of each of said levers on which the levers may rock to engage 70 the sides of the posts with a cramping action; a stem vertically journalled centrally of said clamping member and provided with a cam shaped lower end; sliding plates operable by said cam-shaped end adapted to raise the ends of said levers; and spring means for 75 returning said sliding plates to normal position.

Signed at Toronto, Canada, this 3rd day of February, 1921.

WALTER M. A. GALE
